United States Patent Office

Des. 213,908
Patented Apr. 22, 1969

213,908

BACKPLATE OR THE LIKE

Bernie Bill Baker, Dixon, Ill., assignor to Keystone Consolidated Industries, Inc., a corporation of Delaware

Filed May 24, 1968, Ser. No. 12,064

Term of patent 14 years

Int. Cl. D8—03

U.S. Cl. D8—179

FIG. 1.

FIG. 2.

FIG. 3.

FIG. 4.

FIG. 5.

FIG. 2 is a top plan view thereof;

FIG. 3 is a rear elevational view thereof;

FIG. 4 is an end elevational view thereof; and

FIG. 5 is a cross sectional view thereof taken on the line 5—5 of FIG. 1.

I claim:

The ornamental design for a backplate or the like, substantially as shown.
